JAMES A. HOUSE, OF BRIDGEPORT, CONNECTICUT.

Letters Patent No. 100,764, dated March 15, 1870.

IMPROVEMENT IN FEEDING-MECHANISM FOR SEWING-MACHINE.

The Schedule referred to in these Letters Patent and making part of the same.

To all whom it may concern:

Be it known that I, JAMES A. HOUSE, of Bridgeport, in the county of Fairfield, and State of Connecticut, have invented a new and useful Improvement in Sewing-Machines, of which the following is a full, clear, and exact description, reference being had to the accompanying drawings which make part of this specification, and in which—

Figure 1 represents a plan view of the cloth-plate of a sewing-machine to which my improvement is applied.

Figure 2, a side elevation of the same, partly in section.

Figure 3, a vertical central section through the cam which regulates the length of stitch.

Figure 4, a horizontal section through the cam.

My invention relates more particularly to sewing-machines of the well-known Wheeler & Wilson type, in which the cloth is fed to the needle, to space the stitches by a feed-bar working beneath the cloth-plate. This bar is usually moved in one direction by a cam on the driving-shaft, and in the other by a spring, the retraction of which moves the cloth. In such cases the extent of the movement of the feed-bar, and consequently the length of the stitch, is regulated by means of a cam beneath the cloth-plate.

Now, the object of my invention is to enable the attendant not only to control the length of the stitch, but also to ascertain the exact position of the cam, and to retain the cam, when set, securely in its adjusted position, to which ends

The improvement herein claimed consists in combining a regulating-cam below the cloth-plate with an index-plate above the cloth-plate, and turning with the cam accurately to indicate its position, these parts being constructed to operate as hereinafter set forth.

Also, in combining a cloth-plate and regulating-cam with an index-plate, which also serves as a friction-spring to hold the cam in its adjusted position, as hereinafter described.

The construction and operation of the Wheeler & Wilson sewing-machine being so well known, I have in the accompanying drawings shown only those parts necessary to illustrate the invention herein claimed.

The regulating-cam A is secured to the under side of the cloth-plate B by means of a pin, a, and a screw, a¹. A stud, a², on the pin takes into a slot in the cam and causes the cam to turn with the pin.

The index-plate C has a scale marked on it in such relation to the pin and groove above mentioned that the cam always occupies the same position relatively to the index-plate, the figures on which accurately indicate the number of stitches in a given space.

In order to retain the cam in its adjusted position, and prevent its movement by the jarring of the machine when at work, I make this index in a concave or dished form, the convex side being upward, and thus cause it, when screwed up tightly, to act as a friction-brake or spring to hold the cam securely. (See fig. 3.)

It is obvious that the index-plate might be let into the cloth-plate, so as to be flush with its upper surface, if preferred.

I do not claim broadly the combination of a regulating-cam and an index-plate.

What I claim as my invention, and desire to secure by Letters Patent, is—

The combination, as set forth, of the cloth-plate, the regulating-cam, and the friction-spring index-plate turning with the cam to indicate its position and to measure the stitches, all these parts being constructed and arranged for joint operation, as set forth.

Also, the friction-spring index-plate, constructed, arranged, and operating as set forth.

In testimony whereof I have hereunto subscribed my name.

JAMES A. HOUSE.
